VENTILATED TOILET SEAT

Lucien Couton, 49-51 Rue de Soissons,
Casablanca, Morocco

Filed Aug. 2, 1973, Ser. No. 384,948

Claims priority, application Switzerland Feb. 5, 1973

Term of patent 14 years

Int. Cl. D23—02

U.S. Cl. D23—71

FIG. 1.

FIG. 2.

FIG. 3.FIG. 4.FIG. 1 is a front perspective view of a ventilated toilet seat embodying my new design, showing the cover in a raised position;

FIG. 2 is a side perspective view of FIG. 1;

FIG. 3 is a rear perspective view thereof, showing the cover in its closed position; and

FIG. 4 is a top plan view thereof.

I claim:

The ornamental design for a ventilated toilet seat, substantially as shown.
